UNITED STATES PATENT OFFICE

JAMES E. KREILING, OF CHICAGO, ILLINOIS

HOUSEHOLD BUDGET SYSTEM

Application filed March 19, 1928. Serial No. 262,606.

This invention relates to certain novel improvements in household budget systems, and has for its principal object the provision of an improved arrangement of this type which will be simple in use and economical in manufacture.

A salient object of my invention is to provide a device of the foregoing character embodying a plurality of cards arranged such that entries may be made thereon corresponding to the expenditures and receipts of a household or the like.

Another object of the invention is to provide a card holder which will be arranged so as to embody a pocket in association therewith in which currency or the like may be stored.

A still further object of the invention is to provide a box in which the above mentioned parts may be expeditiously stored, said box being arranged such that it may be locked to prevent unauthorized access thereto.

Other objects will appear hereinafter.

The invention consists in the novel combination and arrangement of parts to be hereinafter described and claimed.

The invention will be best understood by reference to the accompanying drawings, wherein a preferred form of construction is shown, and in which:

Fig. 1 is a perspective elevational view depicting a box of the type which may be used in my device, having a portion of the cards and allied appurtenances mounted therein;

Fig. 2 is a perspective view depicting the card holder employed in my device;

Fig. 3 is a sectional detail view taken substantially on the line 3—3 of Fig. 2;

Fig. 4 is a view taken substantially on the line 4—4 on Fig. 2;

Fig. 5 is an elevational view depicting the card holder in unfolded position;

Figs. 6, 7, 8, 9, and 10 are elevational views depicting forms of cards adapted to be used in the device; and

Fig. 11 is a fragmental view depicting a tab arrangement which may be used in the device.

In the drawings 10 indicates a box or the like which is preferably composed of metal

and which has a hinged lid 11 to which a latching member 12 is attached that engages the spring-actuated latch 13 in order that said lid may be held in closing position. The latch 13 is preferably arranged so as to embody a key operated lock in order that the lid 11 may be locked in closing position with respect to the box 10. In the box 10 a plurality of cards, of a type to be described more fully hereinafter, are arranged and certain of these cards are associated with card holders which will have a pocket associated therewith which are adapted for the reception of currency and the like.

These card holders are best illustrated in Figs. 2 to 5, inclusive, and by referring to Fig. 5, wherein the blank from which the card holder is formed is shown, it may be seen that the card holder includes a front side 14 which preferably has a substantially rectangular opening 15 provided therein. Arranged in horizontal alignment with the front side 14 is a portion 16 and arranged in vertical arrangement with the front side 14 is a portion 17 which includes a flap 18. The edge of the front side 14 opposite to that at which the portion 16 is secured is provided with a tab 19 and the upper edge of the portion 16 as viewed in Fig. 5 is provided with a tab 20. At the point at which the tab 18 is connected to the portion 17 a fold line 21 is provided. A fold line 22 is provided between the juncture of the portion 16 and the front side 14. A fold line 24 is provided between the juncture of the front side 14 and the tab 19, and a fold line 25 is provided between the juncture of the tab 20 and the portion 16.

In assembling the card holder the front side 14 is bent along the fold line 22 so as to be disposed over the portion 17. The portion 16 is folded along the fold line 23 so as to be disposed behind the portion 17, and this folding arranges the tab 19 along one edge of the portion 17 and arranges the tab 20 along the lower edge thereof. The tabs 19 and 20 are then folded so that the tab 19 will be disposed above the edge 26 of the portion 16, which will be disposed along the edge 27 of the portion 17. The portion of the face of the tab 18, which bears on the portion 16, is adhesively

secured thereto and it will be thus seen that a pocket 28 is provided which is closed on its upper side by the flap 18. The flap 20 will be folded so that the fold line 25 thereof will be disposed along the fold line 22 and thus one face of the tab 20 will bear against a portion of the portion 14 along the lower edge thereof and this face of the tab 20 is adhesively secured to the portion 14. It will thus be seen that a pocket 29 is provided which is open along its upper side and therefore, one of the cards to be described herein-after may be inserted into this pocket, and the tab on the card will protrude above the upper edge of the card receiver and the ruled portions of the card will be visible by reason of the opening 15. Inasmuch as the flap 18 closes the upper side of the compartment 28 and inasmuch as this compartment is effectively closed along all the other edges thereof, it is apparent that it may be used for the storage of money and the like, either in the form of coin or paper currency.

In providing a household budget system, I have arranged a plurality of cards in a definite manner which will now be set forth and I have found that by proper use of these cards a very efficient system will result which used properly will effect savings for the user. The face of these cards is indicated at 30 and has a tab 31 provided therein which is adapted to extend above the upper lateral edge of the card. The face of the card is ruled horizontally so as to provide a plurality of spaces 32. Along the right hand edge of the card the spaces 32 are consecutively numbered as indicated at 33 and a vertically extending line intersects the lines providing the spaces 32 so as to provide spaces in which these numbers may be imprinted and this line is indicated by 34 in the drawing. Spaced from and parallel to the line 34 is a line 35 and this line provides in the spaces 32 spaces 36 in which titles corresponding to the numbers in the spaces 33 may be arranged. The remaining portion of the card is preferably divided into four columns 37, 38, 39 and 40 and these columns are preferably ruled with an additional line so as to facilitate the entry of dollars and cents therein.

In starting to use this budget system, it is first necessary that the various items of expenditure of the user be listed in the spaces 36 and these items would be given a corresponding number from the numbers indicated at 33. The column 37 is headed by the title "First estimate" and in this column the user of the device will set down opposite the items in the spaces 36 the amounts he intends to appropriate for the items in these spaces 36. After each of the items listed in the spaces 36 has been appropriated an amount a total is obtained which is entered in the column opposite the word "Totals." If this total is greater or considerably less than the user's income,

changes will be required which are entered in the column 38 under the title of "Corrected estimate," and when these items are added, the totals should substantially equal the user's income. After the foregoing has been completed, the user is then ready to make entries on the item cards which are indicated by 41 in the drawings. These item cards have tabs 42 provided thereon which are preferably disposed so that when the cards are arranged in the box these tabs will be staggered one after the other so as to facilitate the removal thereof from the box 10. On the tabs 42 the numbers and titles from the columns 33 and 36 on the card 30 are printed, and as indicated at Fig. 11 certain of these tabs 42 are arranged so as to be blank in order that the user may fill in any desired title and number. In the present instance item number 13 which is food is depicted on the card 41 and this title and number appears on the tab 42. Obviously, an item such as food is usually purchased for cash and therefore, it is preferable that the card 41 be associated with one of the card holders hereintofore described and generically indicated by 43 in the drawings. The card 41 is inserted into the pocket 29 and as stated hereintofore, the tab 42 projects above the upper edge of the holder 43. On the cards 41 suitable printing is provided which is indicated by 44 in the drawings and in the space provided at 44 the amount listed in the column 38 for the item number 13 is entered. Similarly, the others of the cards 41 corresponding to the titles 36 are so arranged and the items which will be paid for by cash are associated with holders 43. Certain of the items such as for example, rent, would preferably be paid either by check or by amounts drawn from a savings account in the bank, therefore, it is not necessary that these cards be associated with holders 43 but they will be merely inserted in proper order in the box 10. After the foregoing disbursements or appropriations have been made and the proper amount of money has been introduced into the pockets 28 of the holders 43 which are associated with certain of the cards 41, the user will then deposit the remaining balance in the bank either in a checking or savings account, or both if desired, disbursement being made according to the estimates made. The cards 41 are arranged so as to have a plurality of columns thereon, one of which is arranged for the date, and another for the explanatory cause

for the entry to be made in the remaining columns which are headed, "In" and "Out" and "Balance", the "Balance" column being arranged so that at all times it will show the amount of currency in the pocket 28 appropriated to the card or the amount in the checking or savings account which has been appropriated for the item on this card. Additional cards are provided, one of which is indicated by 45. This card 45 has a tab 46 bearing the

title, "Summary cash-card A". Another card 47 is provided which has a tab 48 that bears the title, "Summary checking account—Summary card B," and still another summary card is provided which is indicated by 49 in the drawings, which has a tab 50 that bears the title, "Summary savings account—Summary card C." The summary cards B and C, which relate to Savings and checking accounts have entries made thereon only of the amounts which are in excess of those required by the cards. Therefore, if when making disbursements for the various cards, deposits are made in either of these accounts which are to be withdrawn in order to meet items on the cards 41, these amounts are not entered on the summary cards. As stated, these cards are merely for surplus amounts.

At the end of the period for which the cards 20 are adapted to run, which will preferably be the end of an income-receiving period, and this will be dependant upon whether the income is weekly, semi-monthly or monthly, or in any other manner, it is desirable that the 25 items be balanced. This is done by checking up the amounts in the balance columns in the cards 41. If at the end of the period it is found that there is surplus cash credited to any one of these cards, this surplus cash is 30 entered on summary card 45 in the proper space which will be apparent by referring to Fig. 7, which depicts this card. This card is arranged such that the disbursements made of the excess cash may be indicated thereon 35 and this cash may be distributed in any manner desired by the user, for example, a portion of it may be entered in a savings account, and another portion in a checking account, and if a remaining portion is to be distributed 40 in any manner not specifically accounted for herein, this will be distributed under the disbursement heading of "Miscellaneous." If any of the excess amounts in the summary 45 card A are to be credited to either savings or checking accounts, these amounts are placed on the proper card 47 or 49. After the system has been used it will be possible to enter 50 on the estimate card in the column 39 headed "Period average" the average amounts which were required by the items in the column 36 and at the end of a year or other definite time the total amount disbursed on each item may be entered on the column 40 which is headed in the present instance 55 "Year's out-go."

It is apparent from the foregoing description that I have provided a system for budgeting a household or the like which is arranged such that a very accurate check-up may be 60 maintained on the various items, on which the income is expended, and in this manner a check-up may be made of items on which too much or too little is being expended. In addition to the foregoing, the device is arranged 65 so that cash and the like may be expeditiously

associated with the cards adapted to have the entries of the disbursements made thereon and in view of the fact that the device may be mounted in a lock box it is apparent that unauthorized access to the cards may be prevented.

While I have illustrated and described the preferred form of construction for carrying the invention into effect, this is capable of variations and modifications, without departing from the spirit of the invention. I therefore do not wish to be limited to the precise details of construction set forth, but desire to avail myself of such variations and modifications as come within the scope of the appended claims.

Having thus described my invention, what I claim as new and desire to protect by Letters Patent is:

1. A blank for an envelope comprising a front portion having an opening therein, a portion disposed in horizontal alignment with said front portion and connected thereto along one edge, another portion disposed in vertical alignment with said front portion and connected thereto along one edge, said front portion having a flap formed thereon along the edge opposite said edge having said horizontally aligned portion connected thereto, said horizontally aligned portion having a flap formed thereon on the upper edge thereof, and a flap formed on the upper edge of said vertically aligned portion.

2. An envelope comprising a front portion having an opening therein, a portion formed integral with said front portion joined thereto along the upper edge of said front portion, a member disposed behind said second-named member and connected to said front portion along one edge thereof, said front portion having a flap formed on the edge thereof opposite the edge connected to said last-named portion, said flap being adhesively secured to said last-named portion when in folded position, said last-named portion having a flap disposed along the upper edge thereof and adhesively secured to said front portion, said portions being disposed such that when folded they will form two pockets, and a flap formed on the upper edge of said second-named portion adapted to close the pocket disposed to the rear of the pocket adjacent said front wall.

In testimony whereof I affix my signature.
JAMES E. KREILING.
